UNITED STATES PATENT OFFICE.

GILBERT F. QUINN, OF BOSTON, MASSACHUSETTS, ASSIGNOR TO SIMPLEX RUBBER COMPANY, OF BOSTON, MASSACHUSETTS.

DESIGN FOR A RUBBER HEEL.

60,428.

Specification for Design.

Patented Feb. 14, 1922.

Application filed April 27, 1921. Serial No. 464,996. Term of patent 14 years.

To all whom it may concern:

Be it known that I, GILBERT F. QUINN, a citizen of United States, residing at Boston, in the county of Suffolk and State of Massachusetts, have invented a new, original, and ornamental Design for Rubber Heels, of which the following is a specification, reference being had to the accompanying drawing, forming part thereof.

Figure 1 is a top plan showing the ornamental tread surface of the heel;

Fig. 2 is a side elevation; and

Fig. 3 is a bottom plan, showing the original and ornamental construction of the interior of the heel, and

Fig. 4 is a front elevation or edge view of the breast of the heel.

I claim:

The ornamental design for a rubber heel as shown.

GILBERT F. QUINN.
